UNITED STATES PATENT OFFICE

2,373,210

SPANNER RATCHET WRENCH

Gerrit Van Genderen, Royal Oak, Mich.

Application March 6, 1943, Serial No. 478,176

1 Claim. (Cl. 81—90)

This invention relates to spanner wrenches. It is particularly directed to a ratchet type spanner wrench.

An object of this invention is to provide a wrench of the character described which will ratchet a half turn to greatly facilitate removing of plugs and for the like purposes.

A further object of this invention is to provide a strong, durable and rugged wrench of the character described which shall be easy to manipulate, relatively inexpensive to manufacture and yet practical and efficient to a high degree in use.

Other objects of this invention will in part be obvious and in part hereinafter pointed out.

The invention accordingly consists in the combination of steps, features of construction, combinations of elements and arrangement of parts which will be exemplified in the construction hereinafter described, and of which the scope of application will be indicated in the following claim.

In the accompanying drawing, in which is shown one of the various possible illustrative embodiments of this invention,

Fig. 1 is a side elevational view of a wrench embodying the invention;

Fig. 2 is a bottom plan view thereof;

Fig. 3 is a view similar to Fig. 1 but illustrating a modified construction; and

Fig. 4 is a bottom plan view of the structure shown in Fig. 3.

Referring now in detail to the drawing, 10 designates a spanner wrench of the pin type embodying the invention. The wrench 10 comprises a jaw 11, said jaw 11 consists of a rod 12 of rectangular cross section. Attached to the rear end of rod 12 are a pair of parallel similar plates 13 extending downwardly therefrom and forming a channel 14 therebetween. The plates 13 may be attached to rod 12 by means of a plurality of transverse pins 16 press-fitted through aligned openings in the plates and rod. The plates 13 are formed with slots 17 and the upper edges of the slots are formed with ratchet teeth 18. The teeth 18 are disposed below the rod 12 as shown on the drawing. Pivoted to jaw 11 is a jaw 20. The same comprises a rod likewise of rectangular cross section and preferably of the same stock as rod 12. The rear end of jaw 20 fits within the channel 14 between the plates 13.

Fixed to the rear end thereof is a transverse pin 21 extending through slots 17. The pin 21 extends beyond rod 20 as shown in the drawing. The pin 21 is adapted to engage the ratchet teeth

18 so as to lock the jaw 20 against sliding movement relative to jaw 11 in a rearward direction while permitting the pin to slide forwardly beneath the teeth 18. Attached to the front end of rod 12 is a transverse pin 25 projecting from opposite sides of said rod. Attached to the front end of rod 20 is a transverse pin 26 likewise extending to opposite sides of said jaw. The pins 25 and 26 are adapted to engage in openings in a plug. It will be noted that jaw 20 may move angularly relative to jaw 11 so as to fit different size plugs or for different spacing of holes or openings to be engaged by the pins 25 and 26.

The operation of the device will be understood.

15 The pins 25 and 26 are first engaged in the opening of the article to be turned. Member 10 is then moved in a counter-clockwise direction, causing pin 21 to move forwardly to the left end of slots 17. The device is then turned in a clockwise direction causing the pin 21 to engage one of the ratchet teeth thus fixing the jaws so that the wrench will turn the article engaged by the pins 25, 26. In Figs. 3 and 4 there is shown a wrench 10a embodying the invention and illustrating a modified construction. The wrench 10a comprises a rod 30 to the rear end of which there is attached a pair of plates 31 similar to the plates 13 by means of pins 16a. The plates 31 likewise have slots 32, the upper jaws of which are formed with ratchet teeth 33. Extending between the plates 31 is the rear end of rod 35 which has a pin 36 projecting into the slots 32. The forward end of rod 30 is formed with a slot 37 and the forward end of rod 35 is formed with a similar slot. Pivoted to the forward ends of rods 30, 35 is a hook shaped member 38. Said hook shaped member 38 has ears 39 and 40, received within the slots at the forward ends of rods 30, 35. The ears 39 and 40 are pivoted to said rods by means of pins 42 and 43, and shown in the drawing. The hook 38 has a projection 42 to engage in an opening.

The operation of member 10a is similar to the operation of member 10.

45 It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letter's Patent:

A spanner wrench comprising an elongated rod, a pair of plates secured to opposite faces of the rod adjacent one end of the rod forming a channel therebetween, said plates extending downwardly from the rod and each having a longitudinal slot in the downwardly extending portion, the upper edge of the plate defining each slot having a

series of ratchet teeth, a second elongated rod having one of its ends within said channel, a transverse pin projecting through the end of said last mentioned rod within said channel for coaction with said ratchet teeth, and a transverse pin secured to the opposite free end of each of said rods.

GERRIT VAN GENDEREN.
